UNITED STATES PATENT OFFICE.

EDWIN BALL STIMPSON, OF NEW YORK, N. Y., ASSIGNOR TO EDWIN B. STIMPSON COMPANY, OF BROOKLYN, NEW YORK.

BAG.

1,138,699.

Specification of Letters Patent.

Patented May 11, 1915.

Application filed August 28, 1913. Serial No. 787,125.

To all whom it may concern:

Be it known that I, EDWIN BALL STIMPSON, citizen of the United States, residing at the borough of Brooklyn, city of New York, in the county of Kings and State of New York, have invented certain new and useful Improvements in Bags, of which the following is a specification.

This invention relates to improvements in bags, and will be found particularly valuable in connection with moth-proof bags of the class wherein the bag (whether of the collapsible type or not), and usually the interior of said bag, is provided with hooks or equivalents for the suspension of garments or the like.

One of the objects of this invention is to disclose a type of bag construction, and especially adjacent the mouth thereof, adapted to render a moth-proof closure thereof of greater efficiency than has been possible heretofore.

Another object of the invention is to disclose means for arranging and supplying hooks or equivalents adjacent the mouth of the bag, of an improved and exceedingly inexpensive nature.

Other objects of the invention will be in part obvious and in part pointed out hereinafter.

In the accompanying drawing, wherein is shown one of the various possible embodiments of this invention, Figure 1 is a view in perspective, partly broken away, and showing a bag disclosing a preferred form of mouth construction; Fig. 2 is an elevation of one of the two supporting plates which in the present instance coöperate to arrange said hooks or equivalents adjacent the mouth of the bag; Fig. 3 is an elevation of the other of said plates; Fig. 4 is a sectional view, taken on the line 4—4 of Fig. 3 and looking in the direction of the adjacent arrows; Fig. 5 is a view taken on the line 5—5 of Fig. 2 and on the line 5'—5' of Fig. 3, showing in section and in coupled relation the two plates respectively shown in said Figs. 2 and 3; and Fig. 6 is an enlarged detail view, showing in perspective certain of the parts shown in Fig. 1 after said parts have been partially manipulated to close the mouth of the bag.

Similar reference characters refer to similar parts throughout the several views of the drawing.

Referring now particularly to Figs. 1 and 6, the reference numeral 1 indicates the body-portion of the bag, and it will be seen that in the present instance the walls of this body portion, including the front wall 2, the rear wall 3, the side-wall collapsible sections 4 and 4', the opposite side-wall collapsible sections 5 and 5', the flaps 8, 9 and 9', and the flaps 10 and 10', are formed in the main of a single sheet of material with overlapping terminal portions as shown at 6 in Fig. 1. A reinforcing band 7 completely encircles the mouth of the bag, and lies just below the level of the above-mentioned flaps. This band, opposite the front wall 2 of the bag, carries an integral strip 11, and with the strip overlapped as shown in Fig. 1 a stiffening rod of bamboo or other material 12 is accommodated and held in place between the band 7 and the strip 11.

Still referring primarily to Fig. 1, it will be seen that the hook-carrying plate 13 shown in Figs. 3, 4 and 5, is here interiorly carried by the bag 1, adjacent the mouth thereof and preferably in such manner that the hooks 14 are so arranged as to be capacitated to suspend therefrom for accommodation within the bag a plurality of garments or the like. The plate 14 is affixed in place by means of the coöperation of each of the prongs 16 with a registering aperture or slot 17 formed in the suspending plate 18; this plate 18 being here located exteriorly of the bag 1 but in such a position that the prongs 16, after piercing the bag-wall 3, may pass through the apertures 17 and be clenched on the exterior face 15 of plate 18 as shown in Fig. 5. It should here be observed that in Fig. 5 a sectional view of the wall 3 of the bag 1 is not shown as engaged between the plates 13 and 18, inasmuch as the preferably flexible reinforcing plate 19 shown in Fig. 1 may or may not be utilized; the arrow 20 in Fig. 5, however, indicating the general interposed location of the sheet or sheets of bag or other material located between the plates 13 and 18.

The plate 18 will be seen here to constitute a plate proper having formed therein a plurality of apertures 17, and a beaded upper edge portion 21. This beaded edge portion accommodates as disclosed the free ends of a preferably unitary and preferably wire bail 22, the bail being here medially bent upon itself as illustrated in Fig. 2 to form

the hook 23. It will thus be seen that the body of the bag, the inner plate 13, the hooks 14, the outer plate 18 and the hook 23 mutually coöperate to stiffen and strengthen 5 the bag, and to afford convenient suspending means for both the bag and its contents as well as independent suspending means for 10 said contents, such as garments or the like, interiorly of said bag; and all accomplished by the combination of a very small number 15 of easily assembled parts, each of which parts is exceedingly inexpensive of manufacture. In this connection, it should be noted that each of the plates 13 and 18 is 20 obviously capable of being punched at one operation out of sheet material or the like to establish not only the outlines but the beaded edge portion of the one and not only the outlines but the apertures, prongs and hooks of the other.

The method of closing the bag-mouth made possible by the provision of the flaps 8, 9, 9', 10 and 10' is a very simple and obvious operation, as will be seen from Fig. 1, 25 which as aforesaid shows the mouth of the bag open, and from Fig. 6, which as aforesaid shows the mouth of the bag partially closed; it being merely necessary to understand that the flap 8 finally overlies the strip 30 11 of the band 7 and the previously intucked flaps 9, 9', 10 and 10'. The bag will thereupon be closed in an absolutely moth-proof and dust-proof manner, especially at points adjacent the ends of the flap 8, whereat 35 heretofore much trouble has been experienced in effecting a tight closure; and the said flap 8 will overlie the rounded portion of strip 11 where the latter accommodates the rod 12.

40 Inasmuch as many changes could be made in the above construction, and many apparently widely different embodiments of this invention could be made without departing from the scope thereof, it is intended 45 that all matter contained in the

above description or shown on the accompanying drawing shall be interpreted as 50 illustrative and not in a limiting sense. It is also to be understood that the language used in the following claims is intended to cover all the generic and specific features of the invention herein described and all statements of the scope of the invention which, as a matter of language, might be 55 said to fall therebetween.

Having described this invention, what I claim as new, and desire to secure by Letters Patent, is:

1. In combination with the wall of a bag, a suspension plate on the outside thereof, 60 and a second plate on the inside thereof, the outside plate having its upper edge turned over to form a bead, a suspension hook having portions sprung into said turned-over portion of the outside plate, the second plate 65 having a row of integrally formed hooks projecting forwardly into the bag, one of the plates having a plurality of rows of integrally formed prongs extending through the back wall and the other plate having a 70 corresponding plurality of rows of apertures to be entered by the prongs.

2. In combination with the body walls and mouth of a bag, said body walls including side plications, a reinforcing strip about 75 the mouth of the bag, a stiffening element at the front of the bag, the back wall and side plications of the bag being extended upwardly above the level of said reinforcing strip and above said stiffening element, and 80 a suspension plate connected to the back wall and extending transversely thereof below the upper level of said reinforcing strip.

In testimony whereof I affix my signature in presence of two witnesses.

EDWIN BALL STIMPSON
